UNITED STATES PATENT OFFICE.

MICHAEL CROUGH, OF ILION, NEW YORK.

SAFETY RAZOR.

Application filed May 24, 1923. Serial No. 641,123.

To all whom it may concern:

Be it known that I, MICHAEL CROUGH, a citizen of the United States, residing at Ilion, in the county of Herkimer and State 5 of New York, have invented new and useful Improvements in Safety Razors, of which the following is a specification.

This invention relates to certain new and useful improvements in safety razors, and 10 one object of the invention is to provide a razor of this type which is of simple construction, inexpensive of manufacture, of general maximum efficiency in use, and capable of being readily and conveniently 15 cleansed and maintained in a sanitary condition.

Another object of the invention is to provide a razor which admits of the use of blades which may be rehoned from time to 20 time until the blades are worn out.

Still another object of the invention is to provide a razor which admits of the use of a blade of narrow width or depth and which is so supported as to admit shaving of the 25 upper lip or other angular portions of the face in a ready and convenient manner without interference from the nose or other portions of the face.

Still another object of the invention is 30 to provide a razor having opposed angularly related blade supporting portions, adapted to hold a pair of opposed or oppositely projecting blades, so that the user, by merely reversing the razor, may use one blade for 35 coarse shaving and the other blade for close shaving, or, in case of the dulling of one blade, may reverse the razor to allow the other blade to be used.

Still another object of the invention is 40 to provide simple, reliable and efficient means for holding and clamping the blades in position for use.

With these and other objects in view, the 45 invention consists of the features of construction, combination and arrangement of parts, hereinafter fully described and claimed, reference being had to the accompanying drawing, in which:

Figure 1 is a perspective view of a safety 50 razor constructed in accordance with my invention.

Figure 2 is a central vertical transverse section through the same.

Figure 3 is a longitudinal section taken on 55 the line 3-3 of Figure 2.

Figure 4 is a fragmentary perspective view of one of the blade supporting portions of the comb plate.

In carrying my invention into practice I provide a safety razor comprising a suitable 60 handle 1 having at one end a milled grip portion 2 and having its other end 3 square to form a plane abutting surface, said end 3 being formed with an internally threaded 65 socket 4.

The end 3 is designed to support a double 70 comb plate 5, which is substantially V-shaped in cross-section so as to provide the oppositely disposed or projecting blade supporting portions 6 joined at their inner 75 edges by an intermediate connecting portion 7.

The blade supporting portions 6 are designed to extend outwardly at oblique angles 80 beyond opposite sides of the handle 1 and 75 the straight transverse connecting portion 7 is designed to rest upon the square shoulder 85 of the handle and is formed at a central point with an opening 8 for passage of a fastening screw 9, which screw enters the threaded socket 4 of the handle and fastens 90 the comb plate in position thereon. Each blade supporting portion 6 is slotted at its outer longitudinal edge to provide the comb teeth 10 having the downwardly bent guard 95 portions 11, and each supporting portion 6 is also provided along its end edges with in-turned flanges 12 spaced from the upper surface of the body of the plate to form the blade retaining grooves 13.

The blade supporting portion 6 may be 100 made of comparatively narrow width to support comparatively narrow blades 14. These blades 14 may be of standard length, and each is provided with one longitudinal cutting edge 15, but preferably the blades employed are comparatively narrow in width. Each blade, of which one may be supported by each blade supporting portion 6, rests upon its blade supporting portion of the comb plate and is held in position thereon so that its cutting edge 15 projects beyond the outer edge of the supporting portion 6 and over the comb teeth 10 and the spaces therebetween to properly dispose such 105 cutting edge for a shaving action and for a safety guarding action in the well known way.

The comparatively narrow blade supporting portion 6 and the blades 14 supported 110

thereby project beyond opposite sides of the handle 1, each at a downward and outward angle, the blade supporting portions 6 and the blades carried thereby thus forming oppositely disposed or projecting cutting surfaces arranged at relatively downward and outward converging angles. Each blade is designed to be slidably fitted in position in the groove 6, and slidably removed therefrom, via the upper ends of said grooves, the groove forming flanges 12 of the respective blade supporting portion 6 being cut away along the line of the cutting portion 7 to provide entrance ways for such purpose. In order to prevent forward displacement of the blades and to limit their forward movement in working position and engaged relation to the comb portions 10, the outer or forward ends of each pair of flanges 12 are bent downwardly as at 16, to close the forward ends of the grooves and to form stops against which the ends of the cutting edge of the blade may bear when the blade is disposed in working position. These stops 16 are preferably bent downwardly on a curved line to form auxiliary guards designed to ride smoothly in contact with the face in the operation of shaving. It will be observed that the angular relationship of the blade supporting portion 6 permits of the ready insertion and removal of a blade to or from the receiving grooves of one blade supporting portion without interference from a blade fitted in the retaining grooves of the other blade supporting portion.

For the purpose of firmly clamping the blades in position against recession or other movement, a spring metal clamping plate 17 is provided. This plate comprises a pair of blade clamping members 18 to engage the respective blades, and a connecting portion or bridge piece 19 joining said members 18. Along its medial transverse line the plate 17 is V-shaped to dispose the members 18 to conform to the arrangements of the blades when applied for use, and at its apex the bridge piece 19 is formed with an opening receiving the head portion 20 of the fastening screw 9, which head portion of the screw is riveted or otherwise fixed thereto, the screw and clamping plate thus forming a fastening unit cooperating with the handle 1 for detachably connecting the parts of the razor together.

When the plate 17 is applied the members 18 thereof overlie the outer portions of the blades 14 and bear at their ends against the inner edges of the flanges 12, while the connecting portion or bridge 19 extends over the connecting portion 7 of the comb plate, the screw 9 extending downwardly therefrom through the opening 8 in the comb plate and into the socket 4 of the handle 1,

thus fastening the parts of the razor together. The members 17 have a slightly greater angle of inclination than the blade supporting portion 6 of the comb plate so that their outer bearing edges 21 will frictionally bear upon the blade 14 adjacent to the cutting edges 15 of the latter, while beyond that point toward the bridge or connecting plate 19 the rear portions of members 18 will be elevated relatively to portions 21 and spaced from the blades and will be connected by the resilient bridge piece 19, from which it will be understood that the blades will be firmly clamped at the points where working pressures fall upon them while the spaced arrangement of the parts referred to allows a resilient motion for a spring clamping action, so that through the adjustable connection between the handle 1 and screw 9 the clamping plate may be drawn down as tightly as desired to clamp the blades as firmly as desired against the comb plate. The outer surfaces of the edges 21 of the blade clamping portions 18 of the clamping plate are beveled, as at 22, in conformity with the bevel of the cutting edges 15 of the blades, so that a smooth riding action of the parts of the razor over the face of the user in the operation of shaving will be ensured.

In the operation of assembling the parts, it will be understood that the comb plate is fitted in position upon the handle with the blades fitted in the grooves thereof, after which the clamping plate is placed over the blades and the fastening screw 9 inserted downward through the opening 8 and the handle 1 then applied and turned up on the screw, thus rigidly fixing the parts together and drawing the clamping plate downward by its spring action so that the parts thereof will clamp the blades firmly in position. The mode of disassembling the parts will be apparent from the foregoing description, and it will thus be understood that the construction is such as to permit of the ready and conveniently disassembly of the parts for packing or other purposes, and for the insertion and removal of blades, as well as the cleaning of the blades, the construction described adapting the razor to be easily and conveniently cleaned and kept in a thoroughly sanitary condition.

In practice, the blades and the blades supporting portions of the comb plate, are preferably made, as previously stated, comparatively narrow and, by reason of this fact, and also by reason of the fact that the opposed blades and blade supporting portions extend at an angle to each other, it will be apparent that either blade of the razor may be employed for shaving the upper lip close to the nose and for shaving other an-

gular portions of the face, since in such operation the inactive blade and its supporting parts will lie at an angle out of the way of the nose or other interfering portions of 5 the face, permitting the working blade to be operated closely to all such obstructions. Also it will be understood that by the use of two opposed blades, arranged as described, one blade may be employed for 10 coarse shaving and the razor reversed and the other blade used for close shaving, or, in case one blade is found to be rather dull for use, the operator may reverse the razor and use the sharper blade. As the blades are 15 adjustable towards the comb portion of the comb plate in their guideways, it will be understood that they may be moved up to an accurate working position, and in practice the guideways may be such as to allow 20 slight play of the blade so that, in the event that the cutting edge thereof is not sharpened in accurate alinement throughout its entire length, the blade may be set at a slight angle to compensate for this defect. As the 25 blade is freely adjustable when the clamping plate is loosened to working position, it will be understood that it may be continuously honed or sharpened and repeatedly reused until worn out, thus avoiding the 30 necessity of frequently discarding blades and the waste and expense incident thereto. For the purpose of sharpening the blades a holder of suitable character may be employed, such as that disclosed in my pending 35 application, Serial No. 636,453, filed May 3, 1923. Other advantages of the invention will be apparent from the foregoing description.

Having thus fully described my invention, I claim:—

A safety razor comprising a handle, a V-shaped comb plate having a central vertex portion to rest upon one end of the handle and oppositely disposed obliquely arranged 40 blade supporting portions at diametrically opposite sides of the handle, each of said blade supporting portions having an outer comb edge, upstanding flanges at the side edges of said portions each having blade retaining grooves closed at their outer ends 45 open at their inner ends, blades adapted to rest upon said blade supporting portions and to slidably engage said grooves at their end edges, a V-shaped resilient clamping member for holding said blades in position, 50 said clamping member comprising plates of a length to snugly fit at their ends against said flanges, the outer faces of said member being in the same plane with the outer faces 55 of said flanges and the main portions of the undersurfaces of said plates normally lying out of contact with the blades and said plates having depressed outer edges bearing on the 60 blades, a bridge piece extending over the vertex portion of the comb plate and connecting said plates, and a fastening and adjusting connection carried by the handle and extending through the vertex of the comb plate and engaging the bridge piece whereby 65 the parts are held assembled, said connection being adjustable to bow or flex said bridge piece so as to cause the resilient body portions of the plates to move toward or from 70 the blades.

In testimony whereof I affix my signature.
MICHAEL CROUGH.
